COMBINED SYRINGE TANK AND HOSE HOLDER

Cova S. Bargas, Hollywood, Calif.

Application November 14, 1956, Serial No. 43,754

Term of patent 14 years

(Cl. D4—3)

FIG' 3

FIG' 4

FIG' 1

FIG' 2

Figure 1 is a front elevational view of a combined syringe tank and hose holder, showing my new design;

Figure 2 is a side elevational view of the device;

Figure 3 is a top plan view of the same; and

Figure 4 is a rear elevation thereof on a reduced scale.

I claim:

The ornamental design for a combined syringe tank and hose holder, as shown.
